RESTORATION OF CAR JOURNAL BRASSES

William T. Bissell and Thomas W. Potter, Indianapolis, Ind., assignors to Journal Box Servicing Corporation, Indianapolis, Ind.

Application June 1, 1936, Serial No. 82,858

4 Claims. (Cl. 308—56)

This invention relates to railway journals and particularly to the brasses commonly employed. The invention has for a primary object the prevention of the tremendous loss now occasioned by the requirement for removing and discarding these brasses in which the babbitt has flowed at its outer edges.

In order to give a better understanding of the invention, it is to be recalled that the ordinary practice in lubricating the journals of railway cars is to employ a waste packing, bearing resiliently against the under side of the journal and serving as a wick to feed oil from the lower part of the box carrying the waste to the journal. The oil carried by the waste to the under side of the journal is carried around by the revolving journal to bring the oil up under the brass on the upper side of the journal which carries the load. It is to be remembered that the car will be moving part of the time in one direction and at other times in the opposite direction so that the oil is required to be fed from the waste around the journal in either direction of movement.

The brasses commonly employed bear over but a fraction of the upper part of the journal. These brasses have an under lining of Babbitt metal or other suitable metal of like nature. It is now a requirement universally followed that when this babbitt becomes compressed and is caused to flow around under the brass under the pressure of the load so that the babbitt actually extends below the under edges of the brass, to remove the brasses in such condition from the journal boxes and substitute in their place new brasses. It generally occurs that these brasses removed have been worn in until there is a substantially complete bearing surface entirely therearound against the journal but still permitting a thin lubricant film to enter thereunder and that this bearing surface is perfectly smooth and in an ideal condition for further use, but by reason of the extension of the Babbitt metal around under the brass edges, the journal will run hot by reason of inability of the oil to be properly cooled as will hereinafter more fully be described.

It is a further important object of our invention to provide a very simple remedy which may be applied directly to the used brasses so that they may be returned to use in a better condition than they were when originally applied to the journal.

These and other objects and advantages of the invention will become apparent to those versed in the art in the following description of

our invention which is illustrated more or less diagrammatically in the accompanying drawing, in which

Fig. 1 is a diagrammatic vertical longitudinal section through a journal box;

Fig. 2, a transverse vertical section on the line 2—2 of the journal and its brass showing the brass in the condition as newly applied;

Fig. 3, a similar section showing the condition of the brass after considerable use;

Fig. 4, a bottom plan view of the used brass; and

Fig. 5, a vertical section through the journal and brass on a line similar to line 2—2 in Fig. 1, on an enlarged scale, showing the used brass in a restored condition.

Like characters of reference indicate like parts throughout the several views in the drawing.

The diagrammatic representation of the journal box is that of a standard arrangement where in the journal 10 extends into the customary box 11 to have a packing of waste 12 saturated in oil carried under the journal and reaching around on the sides to some such elevation as indicated by the dash line 13, Fig. 1. The brass 14 is carried within the box 11 in the regular manner with the wedge 15 thereabove on which the box 11 bears to carry the load.

When the brass 14 is initially applied to the journal 10 in its new condition, the babbitt lining 16 rests on the journal only at the center or crown of the brass so that the babbitt initially has but a very small area of contact along the upper side of the journal 10. It is intended that the babbitt 16 will be brought into conformity with the curvature of the journal 10 through pressure and wear by actual usage under load.

Upon sufficient usage, the babbitt 16 will be changed in shape as to its under contour until it does come down normally into bearing contact with the upper side of the journal 10 entirely around its under surface. When the babbitt has reached such a condition, the bearing will be in an ideal condition where each unit area of the babbitt carries its unit load. In this condition, the bearing would normally run cool were it not for a factor which is introduced by this practice of wearing in the bearing. It is commonly known that the new brass in the condition as shown in Fig. 2 will usually run hotter than will the brass when the babbitt 16 is worn in to approach its full bearing surface.

The limiting factor above indicated is introduced when the babbitt 16, Fig. 3, is so compressed under the load after sufficient usage to

bring the babbitt into full bearing contact with the journal 10 as will cause the babbitt to actually flow out on either under edge of the brass 14 to give the overlapping lips 17. Normally the direction of movement of the car will cause an equal size lip 17 to appear on each side of the brass 14 but this of course depends upon the law of averages and should the car have been moved continuously or mainly in one direction, then 10 of course the lip will appear on the one side toward which the journal revolves. When this lip 17 is formed, the oil carried up around the surface of the journal 10 from the waste 12 comes in contact with this lip 17 at its juncture 15 with the journal surface. Some of the oil will normally be carried around under the babbitt 16 to provide normal lubrication but the lip 17 will serve as a drip collecting member into which the surplus oil will flow and be collected to drop 20 therefrom under the influence of gravity. This dropping oil will strike the journal 10 on its sides and thereby be immediately carried back up toward the lip 17 again without normally reaching the waste 12. Of course when there is 25 sufficient accumulation of oil, being the combined oil carried upwardly by the journal 10 mixing with the oil dripping from the lip 17, the excess quantity will flow back down around the journal 10 to the waste 12. In either event it 30 is to be noted that the oil is in direct contact with the journal 10.

In such a type of bearing, heat is generated by the friction. If this heat is normally dissipated by the oil, the bearing will operate within a safe 35 range of temperature.

We have discovered that this temperature range may be very effectively controlled particularly as relating to the brasses 14 which have been formed to an ideal bearing surface but 40 which carry the objectionable lips 17, by providing means for carrying the oil outwardly on the under edge of the brass 14 a sufficient distance to allow the surplus oil to drop clear of the journal 10 onto the waste 12 therebelow without being in contact with the journal 10 on that downward flow. If this return oil (absorbing the heat from the journal on its upper travel) can be circulated through the waste 12 which is saturated 45 with oil in contact with the wall of the box 11, there will be a sufficient dissipation of heat from this returning oil so that the oil upon returning to the journal 10 to be carried upwardly there again to the brass 14 will have been cooled considerably. We find that this simple method of 50 providing a circulation of oil in the journal box 55 very effectively permits the use of the brass 14 with its babbitt 16 after that babbitt has been brought down to a full bearing area providing this circulation may be maintained.

When the brasses 14 are given their regular inspection and removed from the box 11, they are 60 carefully inspected to determine whether or not the babbitt has formed lips 17. If they have, these lips are removed in any suitable manner 65 such as by a cutting tool 18, Fig. 4, without in any way destroying or affecting the bearing surface of the babbitt 16. We particularly want the lips 17 removed to give a lower edge finish to the babbitt 16 as indicated in Fig. 5 where this edge 70 19 is concave from the under side and preferably spaced above the under edge of the brass 14 on each side. The brass thus treated is returned to the same journal 10 from which it was removed so that the bearing surface formed by that 75 journal in that same babbitt may be again utilized

with that perfect seat which has been produced. Ordinarily as above indicated, the brasses 14 when in the condition as shown in Fig. 3 are discarded and returned to a plant for re-babbitting while a new brass 14 in the condition as shown in Fig. 2 is put in place requiring the wearing in process again. 5

After the babbitt 16 in the brass 14 has been fully seated and the lips 17 removed to give the final edges 19 as shown in Fig. 5, there will be 10 little or scarcely no flow of the babbitt 16 so that the brasses may be utilized for a great length of time. It is to be kept in mind that when the lips 17 are formed there still remains generally a sufficient thickness of babbitt 16 on the brass 15 14 to permit this further use.

Referring now to Fig. 5, assuming the journal 10 to be moving counter-clockwise in the direction indicated by the arrow, oil from the waste 12 will be carried upwardly around the right hand 20 side of the journal into contact with the edge 19 of the babbitt 16. Of course there will be sufficient oil to travel on under the babbitt for the required degree of lubrication. The surplus oil will be turned by the edge 19 to flow outwardly under the velocity of the upcoming oil and travel at least to the edge of the brass 14 as indicated by the drops 20. From this edge, the oil will drop clear of the journal back to the waste 12 where it will intermingle with the large 30 volume of oil and thus become reduced in temperature. The box 11 is of course down where the movement of the car will tend to pull the box 11 through the air sufficiently fast enough to induce a cooling effect. 35

Therefore it is to be seen that our invention provides for the utilization of the brass when its babbitt has reached its desired degree of bearing surface rather than having to discard the brass at that time as has been the usual practice and start all over again with the wearing in again of a new babbitt surface. It is to be noted that in this newly applied babbitt surface as indicated in Fig. 2, the oil circulation as indicated in Fig. 5 can not be maintained and this 45 factor contributes to the higher temperature operating condition of the bearing in this condition.

A further important reason not above enumerated for removing the lips 17 from the Babbitt metal is to prevent the throwing of the oil from the journal box. When the oil builds up in a 50 mass against the journal under the lips 17, this thick mass tends to seek a level and it flows horizontally toward the ends of the brass. The oil flowing to the inner end of the brass strikes the fillet on the journal and of course is carried up onto the larger diameter of the journal and from that diameter the oil will travel inwardly to the wheel and be thrown out. By reason of such action, the oil will soon be pumped out of the box 60 with the result that insufficient oil will remain to effect proper lubrication. Therefore the removal of these lips 17 as above indicated prevents this throwing out of the oil as a further important 65 factor.

While we have herein shown and described our invention in the one best form as now known to us, it is obvious that structural variations may be employed such as varying the shape of the under side of the edge 19, without departing 70 from the spirit of the invention and we, therefore, do not desire to be limited to that precise form beyond the limitations as may be imposed by the following claims.

We claim:

1. That method of securing a cool running journal brass lined with a softer metal, which consists of initially forming the lining metal face to have a bearing radius exceeding that of its 5 service journal, wearing in the lining metal under load in service on its journal to flow the metal around the brass by load pressure and journal friction until a uniform bearing surface of the lining metal against the journal is reached substantially over the entire area of the metal 10 to leave a thin oil film clearance only between it and its journal, said wearing in step causing a flow in part at least of the metal beyond the brass edges, removing the brass from the journal, trimming off that metal which has overflowed the brass edges to leave lining metal edges directing surplus oil outwardly under the brass away from the journal and replacing the trimmed brass on its service journal on which it was worn 15 in.

2. That method of securing a cool running journal brass lined with a softer metal, which consists in placing the brass on a service journal with the lining pressed thereagainst, wearing in the lining metal under load in service 20 on its journal to flow the metal around the brass by load pressure and journal friction until a uniform bearing surface of the lining metal against the journal is reached substantially over the entire 25 area of the metal to leave a thin oil film

clearance only therebetween, said wearing in step causing a flow in part at least of the metal beyond the brass edges, removing the brass from the journal, trimming off that metal which has overflowed the brass edges, and replacing the 5 trimmed brass on its journal on which it was worn in.

3. That method of restoring a used lined brass for a railroad car axle journal, which consists of pulling a brass from the car journal after having served to carry loads in service for a period sufficient to cause the brass lining to flow along the brass edges, trimming off the flowed lining along the brass edge, and immediately placing the trimmed brass back on the same journal from 15 which it was taken for subsequent use thereon.

4. That method of restoring a used lined brass for a railroad car axle journal which consists of lifting the journal box about a journal whose brass has been subjected to service load conditions over a period of time, pulling out the brass for inspection as to flow of lining along the brass edges, trimming off the objectionable flowed lining at the brass edge, replacing the trimmed brass on said journal, and dropping said box to 20 restore said trimmed brass for further service 25 on its original car journal on which it was worn in.
